UNITED STATES PATENT OFFICE.

WILLIAM W. LOWREY, OF NEW YORK, N. Y.

DESIGN FOR A GLASS STOPPER FOR BOTTLES.

SPECIFICATION forming part of Design No. 30,832, dated May 23, 1899.

Application filed April 24, 1899. Serial No. 714,322. Term of patent 3½ years.

To all whom it may concern:

Be it known that I, WILLIAM W. LOWREY, a citizen of the United States, residing at Stuyvesant Place, in the borough of Richmond, city of New York, State of New York, have invented and produced a new and original Design for Glass Stoppers, of which the following is a specification, reference being had to the accompanying drawings, forming part thereof.

Figure 1 represents a front view of the stopper, showing my design. Fig. 2 is an edge view of the same end. Fig. 3 is a transverse section taken on line X X.

As shown in the drawings, the leading or material feature of my design consists of forming the contour of the edge of the head of the stopper by a series of abrupt scroll-like curves

A, the convolute ends B of each curve, as well as the main body thereof, extending inwardly 20 to the bevel C, which terminates in a plane D. The upper convolutes of the aforesaid curves are separated by a palm or fan shaped ornament, forming the crown of the structure. The lower convolutes are separated by a depending beveled collar E, formed on and concentric with the shank F of the stopper. 25

Having described my invention, what I claim as new, and desire to secure by Letters Patent, is—

The design for a glass stopper for bottles as herein shown and described.

WILLIAM W. LOWREY.
